INTERLOCKING MECHANISM

Richard E. Bonin and George R. Townsend, Roanoke, Va., assignors to General Electric Company, a corporation of New York

Application June 17, 1957, Serial No. 666,071

17 Claims. (Cl. 200—50)

This invention relates to interlocking mechanism for circuit control equipment, more particularly to interlocking mechanism for circuit control equipment of the enclosed type having circuit control switches and separate access doors therefore, and it has for an object the provision of a simple, reliable and improved interlocking mechanism of this character. Such control equipment may include high voltage current limiting fuses, high voltage line isolating switches, and contactors of the electromagnetically operated type and their associated control devices mounted in suitable metal cabinets or compartments that may be assembled to meet widely varying circuit control requirements and provided with separate access doors. Although not limited thereto, such variously assembled enclosed equipment is particularly useful in high voltage heavy duty industrial motor control applications.

In conventional methods of mechanical interlocking in which it is desired to have the movement of one member from an initial position depend upon the position of another member or members, it is customary to insert an interlocking linkage in such a manner that if movement of the first member is initiated when the second member is in a position which requires the first member to be retained in its initial position, the first member will be restrained from moving by means of an interlocking linkage bearing directly on some portion of the second member. Interlocking mechanism of this character operates satisfactorily in equipments in which the interlocking linkage is relatively short in length and in which the second member can withstand any force which could be applied to it by the first member. However, in equipments in which a relatively long interlocking linkage is used the interlocking mechanism becomes unstable when relatively large forces are transmitted through the linkage to the second member. In such equipments and in equipments in which for any reason it is undesirable to subject the second member to stresses of the magnitude that it would be possible to transmit to it as a result of force applied to the first member, a conventional interlocking mechanism is unsatisfactory and leave something to be desired. Accordingly, a further object of this invention is the provision of an interlocking mechanism having means for limiting to a predetermined value the magnitude of the force that can be transmitted from the first member to the second member.

In carrying the invention into effect in one form thereof, an operating member and a movable second member are provided together with a linkage member between them which is driven by the operating member. The second member has blocking and non-blocking positions with respect to the driven linkage member. A yielding driving connection is provided between the operating member and the driven member together with interference means for limiting to a predetermined value the force that can be applied by the operating member to the driven member to be transmitted to the second member in its blocking position.

In illustrating the invention in one form thereof, it is shown as embodied in motor control equipment enclosed within a metal cabinet having separate access doors for the isolating switch, meters and instruments, and electromagnetically operated contractor. The invention itself both as to the elements and their organization together with further objects and advantages will best be understood by referring to the following description taken in connection with the accompanying drawings of which

- 10 Fig. 1 is a view in front elevation of a typical multiple tier cabinet assembly for enclosing high voltage three-phase motor control equipment to which the improved interlocking mechanism of the invention may appropriately be applied shown with several of the compartment doors open to reveal the motor circuit control switches therein. Fig. 2 is a fragmentary view in side elevation of the lower portion of the assembly shown in Fig. 1 with portions of the cabinet wall broken away more clearly to reveal the common door latching mechanism. 15 Fig. 3 is a view in perspective of a preferred form of the interlocking mechanism of the invention shown as applied to the interlocking of two switches one located in the top compartment and the other in the bottom compartment of the cabinet of Fig. 1. Fig. 4 is a plan view of a detail 20 of the mechanism illustrated in Fig. 3. Fig. 5 is a front view of a portion of the interlock mechanism of Fig. 3 illustrating the relative positions of parts of the interlocking mechanism during an operating condition in which the second member is in a position which requires 25 that the operating member be prevented from moving from a predetermined initial position. Fig. 6 is a view 30 in front elevation of the upper portion of the mechanism of Fig. 5 showing the relative positions of the parts during another operating condition in which the position of 35 the second member is such that the operating member may be permitted to move from such initial position. Fig. 7 is a view in perspective of a modified form of the interlocking mechanism of Figs. 1 to 6 inclusive, Fig. 8 is a front view of the modified form of Fig. 7 illustrating 40 the relative positions of parts during an operating condition in which the second member which is to be interlocked with the operating member is in a position which requires the operating member to be prevented from moving from a predetermined initial position, and Fig. 9 is a front view of the mechanism of Figs. 7 and 8 illustrating 45 the relative positions of the parts during an operating condition in which the second member is in a position in which movement of the operating member from such initial position is permissible.

Referring now to the drawings and particularly to Fig. 1, in an upper compartment C1 of the enclosing cabinet 1 are mounted the current limit short circuit protective fuses 2 and a three-phase gang disconnect switch 3 for isolating from the power supply lines 4 the fuses, main starting contactor and associated metering and control devices. The arrangement is such as to permit removal and replacement of a blown fuse only when the isolating switch 3 and the access door DC1 are open as shown. This switch is provided with an operating member which is illustrated as a shaft 5. As shown in Figs. 3, 5 and 6, this shaft 5 extends from the rear wall of the compartment C1 to the access door DC1 and is journaled for rotation in a bearing bracket 5a which is secured to the wall of the cabinet 1 by any suitable means such for example as welding. In the end of shaft 5 nearest the compartment access door DC1 is mounted a pin 6. The door-latching and unlatching handle 7 carries a yoke 8 which may be moved into engagement with the pin 6 for closing isolating switch 3 only when the access door is closed. Upon movement of the handle to its down position, the latching dog 9 passes behind the lip 1a of the front cabinet wall and latches the door DC1 closed.

An interlocking linkage rod 10 extends between the operating shaft 5 in the upper compartment C1 and the interference member of a motor-starting switch in the lower compartment C2. This linkage rod 10 is mounted for vertical lengthwise sliding movement in guide brackets 10a and 10b secured to the side wall of the enclosing cabinet. Operation of the handle 7 to its isolating switch-closing and door-latching position raises the interlocking linkage member 10 to move the latch 11 into latching position with the latching bracket 12 carried on the inside of the lower compartment access door DC2. In this manner access to the three-phase high voltage motor-starting switch or contactor 14, which is mounted in the lower compartment C2 and connected in series with the isolating switch 3, is prevented when the isolating switch is closed.

The three-phase motor-starting switch 13 is normally open and is electromagnetically operated to the closed position by means of a suitable electromagnet 14 (see Fig. 2) which may be energized and deenergized by means of suitable manually operated switches, preferably of the pushbutton type, or by automatic control not shown. When energized, the electromagnet 14 rotates the shaft 15 to close suitable three-phase switch contacts which, in accordance with standard practice, may be provided with magnetic blowouts and removable arc chutes 16. Ordinarily, overload protection for the motor circuit is provided so that the electromagnet 14 may be automatically deenergized by means of a suitable overload responsive relay not shown. In any event, reverse rotation of shaft 15 will open switch 13 whenever the operating electromagnet 14 is deenergized.

As the motor-starting switch 14 is closed and opened a bell crank arm 17, extending from the operating shaft 15, moves a link 18 to effect rotation of a motion-amplifying bell crank arm 19 (see Fig. 3) about its pivot pin 20. This pin is mounted on a bracket 21 which extends from the frame of the three-phase motor-starting switch as shown in Fig. 3. The motor switch 13 is provided with an interference member which is illustrated as a bar 22 pivotally connected by means of a pin 23 to the long arm of the motion-amplifying bell crank 19 and through the bell crank to the movable contact-carrying member of the switch. It is mounted to slide in suitable guide blocks 24 and 25 into and out of blocking relationship with the lower end of the interlocking linkage member 10. Thus whenever the motor-starting switch 13 is closed, interference member 22 will slide under the lower end of linkage member 10 to lock the latch 11 in latching relationship with the door latch bracket 12 and also to lock handle 7 in its down position thereby to prevent opening of the isolating switch 3 as long as the motor-starting switch remains closed. At the same time both access doors DC1 and DC2 are locked closed.

In many equipments and installations in which two members are to be interlocked, the distance between them is such as to require a relatively long interlock link. For example in apparatus of the character disclosed in Figs. 1, 2 and 3 the distance between the isolating switch operating member 5 and the interference member 22 of the motor switch 13 may be 72 inches or more thus requiring the interlock link 10 to be of approximately the same length. For the purpose of eliminating from the interlocking mechanism instability produced by such relatively long interlock link and also for the purpose of limiting to a low value the force that can be transmitted by the interlock link 10 to the interference member 22, means are provided for limiting the force that can be applied by the operating member 5 to drive the driven interlock member 10. These means comprise a yielding driving connection between the operating member and the driven member 10 and means for blocking the movement of the operating member if the driven member 10 does not move a predetermined distance from an initial position in response to

a predetermined amount of movement of the operating member from a corresponding initial position. Illustrated as comprising the yielding driving connection and blocking means are an arm 26 keyed to the shaft arm 5 and provided with pins 27 and 28, a bracket 29 secured to the link member 10 and provided with a pin 30 together with a resilient member such as the coil spring 31 connected between the pins 28 and 30 and stressed to bias the bracket 29 into engagement with pin 28. The free end of the bracket 29 is returned at right angles to provide an interference surface in the path of pin 27. For actuating the isolating switch in response to rotation of the operating shaft 5, a toggle mechanism comprising toggle arms 32 and 33 is connected between the shaft and the movable contact-carrying member of the switch.

When the isolating switch is closed, the operating shaft 5, arm 26 and toggle arms 32 and 33 are in the positions in which they are illustrated in Fig. 3. The pins 27 and 28 are located on radii from the center of the shaft which are separated by a substantial angle. It will be noted that in response to rotation of shaft 5 any point on the upper portion of arm 26 such as the square pin 27 will have an initial horizontal movement and that any point well to the right of center, such as pin 28, will have an initial movement in a substantially vertical direction. The initial movement of the junction point of the toggle members 32 and 33 is generally substantially vertical. Consequently there is a substantial rotation of operating shaft 5 before there is any appreciable opening movement of the isolating switch 3. This free movement of the shaft determines the distance between the square pin 27 and the interfering end surface of bracket 29. Successful operation has been obtained with a distance between pin 27 and interfering surface 29a equivalent to 18 degrees of shaft rotation.

For the purpose of preventing closing of the isolating switch with the lower compartment door DC2 open, means are provided for blocking the upward movement of the interlock member 10 until the door is closed. This means is illustrated as a spring biased interference bracket 34 mounted for lengthwise sliding reciprocating movement in a U-shaped bracket 35 which is secured to the guide bracket 10b in a position such that the face of its up-turned end 34a engages the opposing face of the door latch 12 when the door is closed. With the linkage rod 10 in its lower position and the door open, the spring 34b moves the bracket 34 over and past the bent-over end of the latch member 11 as illustrated in Fig. 4 to block upward movement of the linkage rod.

With the foregoing understanding of the elements and their organization, the operation of the interlocking mechanism will readily be understood from the following detailed description. Assuming the isolating switch 3, the motor switch 13 and access doors DC1 and DC2 to be closed, the elements of the interlocking mechanism occupy the positions in which they are illustrated in Fig. 3. The isolating switch is not constructed for current interruption. Consequently the motor switch 13 must be opened prior to opening the isolating switch and similarly the isolating switch must be closed prior to closing the motor switch. As previously pointed out, opening and closing of the motor switch may be accomplished either by automatic or manual control. Opening of the motor switch withdraws its interference member 22 from blocking relationship with the lower end of interlock linkage rod 10. The door handle 7 of compartment C1 may then be rotated in a clockwise direction. Since pin 28 is secured to arm 26 and bracket 29 is biased against the pin by spring 31, and since interference member 22 is clear of the path of interlock linkage rod 10, the latter moves downward carrying with it bracket 29 to permit the square pin 27 to pass over the top edge of the returned end 29a of the bracket without striking its interfering surface, as illustrated in Fig. 6. Consequently, the

clockwise rotation of the operating shaft may be continued to open the isolating switch to disconnect and thus to isolate the accessible high voltage components from the line. Continued rotation of the handle 7 and shaft 5 rotates the movable contacts of the isolating switch into engagement with grounding clips 36 to ground the equipment. The rotation of door handle 7, required to open the isolating switch, turns the latch 9 out of latching engagement with the cabinet lip 1a thus permitting the door DC1 to be opened.

The downward movement of interlock linkage rod 10 lowers the top edge of latching bracket 11 beneath the lower edge of the door latch member 12 as shown in Fig. 4 and thus permits the lower access door DC2 to be opened. In opening, the door withdraws latch member 12 from engagement with the face 34a of bracket 34 thereby to permit the biasing spring 34b to move the bracket over the top edge of the returned end of the latch bracket 11. This prevents upward movement of rod 10 and thus prevents closing the isolating switch 3 as long as the bottom access door DC2 is opened.

If the motor switch 13 had not been opened, its interference arm 22 would be in blocking position with respect to linkage rod 10 as shown in Fig. 3. Consequently, the bracket 29 would have remained in the interfering position illustrated in Figs. 3 and 5 with its interfering surface squarely in the path of the pin 27 on the driving arm 26. After 18 degrees rotation of the operating shaft 5, an amount which is insufficient to open the isolating switch, the pin 27 would engage the interference surface of bracket 29 and further rotation of the shaft would be blocked. During this predetermined limited amount of rotation of shaft 5, the biasing stress of spring 31 would be increased to a corresponding predetermined relatively low value. Any further increase in force applied to rotate the operating shaft after the pin engages bracket 29 is absorbed in the guide 10a which supports the linkage rod 10, and such increased force has no downward component. Consequently, no force in excess of that transmitted by spring 31 is transmitted to the interference arm 22 of the motor switch. Thus the force that can be applied to interference arm 22 is definitely limited to a relatively low value and instability of the interlocking mechanism which might result from application of large forces to drive the relatively long linkage rod 10 is eliminated.

In restoring the equipment to service, the doors DC1 and DC2 are first closed. In the closed position of the door DC2 the door latch member forces the bracket 34 back over the top edge of the latching member 12. The door handle 7 may now be rotated in a counterclockwise direction to close the isolating switch and latch the door DC1. As a result of such counterclockwise rotation of the operating shaft 5, linkage rod 10 is raised to elevate the latching member 11 into latching relationship with door latch member 12 and simultaneously to lift the lower end of the linkage rod 10 out of the path of the interfering member of motor switch 13 which now may be closed.

In the modification which is illustrated in Figs. 7, 8 and 9, two shaft arms are employed, the arm 26 and a second arm 37. The arm 26 is keyed to the operating shaft 5 with its centerline a predetermined angle, e.g. 18 degrees above the horizontal. Arm 37 is free to rotate on the shaft 5, but rests on pin 38 of arm 26 and is biased into engagement with it by means of a torsion spring 39. Pivotally mounted on the supporting bearing bracket 5a is a reaction block 40. In the position in which it is illustrated in Fig. 7 the reaction block 40 is directly in the path of rotation of the arm 26. However, vertical interlock linkage rod 10 is provided with an arm 10d which, if the rod moves downward, rotates the reaction block 40 out of the path of the driving arm 26. The arm 37 is linked by means of a pin and slot connection to the bracket 29 on the vertical rod 10.

If the motor switch 13 is open, its interfering arm 22 does not restrict the downward movement of the vertical rod 10. Consequently if the shaft 5 is now rotated, the vertical rod 10, bracket 29 and arm 10d descend. The downward movement of arm 10d rotates the reaction block 40 out of the path of arm 26 before the shaft has rotated 18 degrees as illustrated in Fig. 9. Consequently the clockwise rotation of the operating shaft 5 may be continued to open the isolating switch and to unlatch the upper and lower compartment doors DC1 and DC2. On the other hand, if the motor switch 13 is closed when the switch shaft is rotated in a clockwise direction, the motor switch interfering arm 22 restricts the downward movement of rod 10, bracket 29 and arm 10d. As a result, the reaction block 40 is not rotated from the position in which it is illustrated, and it will therefore be struck by driving arm 26 when the latter has rotated 18 degrees from its initial position as illustrated in Fig. 8. Any increase in the applied force beyond that which is transmitted through the torsion spring 39 to the vertical rod at the instant of engagement of the driving arm 26 with the reaction block 40 is absorbed by the latter and is not transmitted through the rod 10 to the interference arm 22 of the motor switch.

The interlocking mechanism of the invention could be applied in any apparatus or equipment in which a shaft must be prevented from rotating beyond a predetermined number of degrees or a member must be prevented from moving when the position of some remote device or devices makes further rotation hazardous to life or equipment.

Although in accordance with the provisions of the patent statutes, this invention has been described as embodied in concrete form, and its principle of operation has been explained together with the best mode in which it is now contemplated carrying that principle into effect, it will be understood that the apparatus shown and described is merely illustrative and that the invention is not limited thereto since alterations and modifications will readily suggest themselves to persons skilled in the art without departing from the true spirit of the invention or from the scope of the annexed claims.

What we claim as new and desire to secure by Letters Patent of the United States is:

1. An interlocking mechanism comprising a movable operating member, a driven member, a yieldable driving connection between said members, a movable member having blocking and non-blocking positions with respect to the movement of said driven member, and interference means responsive to relative movement of said operating member and said driven member for limiting to a predetermined value the force transmitted by said driven member from said operating member to said movable member in its blocking position.
2. An interlocking mechanism comprising an operating member movable between first and second operating positions, a driven member, a yieldable driving connection between said members, a movable member having blocking and non-blocking positions with respect to the movement of said driven member, and interference means for limiting to a predetermined value the force transmitted through said yieldable connection to said driven member comprising means mounted in position to block said operating member at an intermediate point in its movement between said operating positions and removable therefrom in response to a predetermined amount of movement of said driven member from an initial position prior to arrival of said operating member at said intermediate point.
3. An interlocking mechanism comprising an operating member, a driven member, a yieldable driving connection between said members, a movable member having blocking and non-blocking positions with respect to the movement of said driven member, and interference means comprising a projection on said operating mem-

ber having an initial direction of movement angularly disposed with respect to the direction of movement of said driven member and a blocking member disposed in the path of said projection and removable from said path in response to a predetermined amount of movement of said driven member from an initial position.

4. An interlocking mechanism comprising in combination, an operating member, a driven member having a rectilinear movement, a yieldable driving connection between said members, a movable member having blocking and non-blocking positions with respect to said driven member, and interference means for limiting to a predetermined value the force transmitted through said driving connection to said driven member comprising means interposed to block said operating member at the end of a predetermined amount of movement from an initial position and removable from blocking engagement therewith in response to a predetermined amount of said rectilinear movement of said driven member from an initial position.

5. An interlocking mechanism comprising an operating member, a driven member, a yieldable driving connection between said members, a movable member having blocking and non-blocking positions with respect to the movement of said driven member, and interference means comprising a blocking member, means for mounting said blocking member in a position to block said operating member at the end of a predetermined amount of movement from an initial position and means responsive to a predetermined amount of movement of said driven member from an initial position for removing said blocking member from its blocking position.

6. An interlocking mechanism comprising in combination an operating member, a driven member, a yieldable driving connection between said members and interference means for limiting to a predetermined value the force transmitted from said operating member to said driven member comprising a member carried by said driven member and positioned to block said operating member in the event of non-movement of said driven member in response to a predetermined amount of movement of said operating member.

7. An interlocking mechanism comprising an operating member having an initial position, a driven member having an initial position, a yieldable driving connection between said members, a movable member having blocking and unblocking positions with respect to the movement of said driven member and interference means for blocking said operating member after a predetermined amount of movement from its initial position thereby to limit to a predetermined value the force transmitted by said driven member to said movable member in its blocking position, and means responsive to a predetermined amount of movement of said driven member from its said initial position for moving said interference means out of blocking relationship with respect to said operating member.

8. An interlocking mechanism comprising in combination an elongated rod-like driven member having an initial position, means mounting said member for lengthwise rectilinear movement, operating means comprising a rotatably mounted shaft and an arm mounted on said shaft for rotation therewith and having an initial position, a first portion of said arm having an initial movement generally in the direction of said lengthwise movement and a second portion of said arm having an initial movement in a direction generally perpendicular to the direction of said lengthwise movement, a yieldable driving connection between said first portion and said driven member, means for limiting to a predetermined value the force transmitted through said driving connection to said driven member comprising a bracket member mounted on said driven member in position to block said second portion of said arm in the event of less than a predetermined amount of movement of said driven member from

its said initial position in response to a predetermined amount of movement of said arm from its said initial position.

9. An interlocking mechanism comprising in combination an elongated rod-like driven member having an initial position, means mounting said member for lengthwise rectilinear movement, operating means comprising a rotatably mounted shaft and an arm mounted on said shaft for rotation therewith and having an initial position, a first portion of said arm having an initial movement generally in the direction of said lengthwise movement and a second portion of said arm having an initial movement in a direction generally perpendicular to the direction of said lengthwise movement, a bracket member mounted on said driven member in the path of movement of said second portion of said driving member when said driven member is in its said initial position, a yieldable driving connection between said first portion of said driving member and said bracket member for transmitting to said driven member a driving force in the direction of its rectilinear movement, said bracket member acting to block said driving member in the event of less than a predetermined amount of movement of said driven member from its said initial position in response to a predetermined amount of movement of said driving member from its said initial position.

10. An interlocking mechanism comprising in combination an elongated rod-like driven member having an initial position, means mounting said member for lengthwise rectilinear movement, a rotatably mounted shaft, a driving arm mounted on said shaft for rotation therewith having an initial position, a first projection on said arm having an initial movement generally in the direction of said rectilinear movement, a second projection on said driving arm having an initial movement in a direction generally perpendicular to the direction of said lengthwise movement, a bracket member mounted on said driven member in the path of said initial movement of said second projection when said driven member is in its said initial position, a yieldable driving connection comprising a spring connected between said first projection and said bracket for transmitting to said driven member a force to drive it in the direction of said rectilinear movement to move said bracket out of the path of said second projection, said bracket acting to block said driving member in the event of less than a predetermined amount of movement of said driven member from its said initial position.

11. In combination a first switch having a movable contact-carrying member, a second switch having a movable contact-carrying member and interlocking mechanism for said switches comprising a driving member operatively connected with the movable contact-carrying member of said first switch, a driven member, a yieldable driving connection between said driving and driven members, an interfering member operatively connected with the movable contact-carrying member of said second switch having blocking and non-blocking positions with respect to the movement of said driven member, and interference means responsive to relative movement of said driving member and said driven member for limiting to a predetermined value the force transmitted by said driven member from said driving member to said interfering member.

12. In combination a first switch having a movable contact-carrying member, a second switch having a movable contact-carrying member and interlocking mechanism for said switches comprising a driving member operatively connected with the movable contact-carrying member of said first switch, a driven member, a yieldable driving connection between said driving and driven members, an interfering member operatively connected with the movable contact-carrying member of said second switch having blocking and non-blocking positions with respect to the movement of said driven member and interference

means comprising a projection on said driving member having an initial movement in a direction angularly disposed with respect to the direction of movement of said driven member and a blocking member disposed in the path of said initial movement and removable from said path in response to movement of said driven member.

13. In combination a first switch having a movable contact-carrying member, a second switch having a movable contact-carrying member and interlocking mechanism for said switches comprising a driving member operatively connected with the movable contact-carrying member of said first switch, a driven member, a yieldable driving connection between said driving and driven members, an interfering member operatively connected with the movable contact-carrying member of said second switch having blocking and non-blocking positions with respect to the movement of said driven member, and interference means for limiting to a predetermined value the force transmitted by said driven member to said interfering member comprising a blocking member, means for mounting said blocking member in a position to block said driving member at the end of a predetermined amount of movement of said driven member from an initial position and means responsive to a predetermined amount of movement of said driven member from an initial position for removing said blocking member from its blocking position.

14. In combination a first switch having a movable contact-carrying member, a second switch having a movable contact-carrying member and interlocking mechanism for said switches comprising an operating member, driving connections between said operating member and the movable member of said first switch providing a predetermined amount of movement of said operating member from an initial position while maintaining said contact-carrying member of said first switch in switch-closed position, a driven member, a yieldable driving connection between said operating member and said driven member, an interfering member operatively connected with the movable contact-carrying member of said second switch having blocking and non-blocking positions with respect to said driven member, and interference means for limiting to a predetermined value the force transmitted from said operating member to said interfering member comprising a member carried by said driven member and positioned to block said operating member in the event of non-movement of said driven member in response to said predetermined amount of movement of said operating member from said initial position.

15. In combination a first switch having a movable contact-carrying member a second switch having a movable contact-carrying member and interlocking mechanism for said switches comprising an elongated rod-like driven member having an initial position, means mounting said driven member for lengthwise rectilinear movement, operating means comprising a rotatably mounted shaft and an arm mounted on said shaft for rotation therewith and having an initial position, driving connections between said shaft and the movable member of said first switch providing a predetermined amount of rotation of said shaft and said arm from an initial position while maintaining said contact-carrying member in the switch-closed position, a first portion of said arm having an initial movement generally in the direction of said lengthwise movement and a second portion of said arm

having an initial movement in a direction generally perpendicular to the direction of said lengthwise movement, a yieldable driving connection between said first portion and said driven member, an interfering member operatively connected with the movable contact-carrying member of said second switch having blocking and non-blocking positions with respect to said driven member and interference means for limiting to a predetermined value the force transmitted from said operating means to said interfering member comprising a bracket member mounted on said driven member in position to block the movement of said second portion of said arm in the event of less than a predetermined amount of movement of said driven member from its said initial position in response to said predetermined amount of rotation of said arm from its said initial position.

16. An interlocking mechanism comprising an operating member having an initial position, a driven member having an initial position, a movable member having blocking and non-blocking positions with respect to the movement of said driven member, an arm mounted on said operating member for movement therewith, a yieldable driving connection between said arm and said driven member, means for blocking said operating member after a predetermined amount of movement from its said initial position thereby to limit to a predetermined relatively low value the force transmitted by said driven member to said movable member in its blocking position comprising an interference member pivotally mounted in blocking relationship in the path of said arm, and means responsive to a predetermined amount of movement of said driven member from its said initial position for rotating said interference member out of blocking relationship with respect to said arm.

17. An interlocking mechanism comprising an operating shaft having an initial position, a driven member having an initial position and provided with a bracket having a slot, a movable member having blocking and non-blocking positions with respect to the movement of said driven member, a first arm fixedly mounted on said shaft for rotation therewith and provided with a pin, a second arm loosely mounted on said shaft and provided with a pin engaging said slot, a yieldable driving connection between said pins, means for blocking said operating member after a predetermined amount of movement from its said initial position thereby to limit to a predetermined relatively low value the force transmitted through said driven member from said operating member to said movable member in its blocking position comprising a reaction block pivotally mounted in blocking relationship in the path of said first arm, and a projection carried by said driven member for rotating said reaction block out of blocking relationship with respect to said first arm in response to a predetermined amount of movement of said driven member from its said initial position.
